UNITED STATES PATENT OFFICE.

FRANK C. MERRILL, OF MARINE CITY, MICHIGAN.

ENGINE-MANIFOLD.

1,160,744.

Specification of Letters Patent. Patented Nov. 16, 1915.

Application filed December 16, 1914. Serial No. 377,573.

To all whom it may concern:

Be it known that I, FRANK C. MERRILL, a citizen of the United States, residing at Marine City, in the county of St. Clair and State of Michigan, have invented a new and useful Engine-Manifold, of which the following is a specification.

The present invention appertains to a manifold for internal combustion engines, and aims to provide an intake and exhaust manifold of novel construction, whereby the heat of the exhaust or burnt gases will be utilized for heating the gaseous vapor or carbureted air, to increase the effectiveness of the fuel even though a poor grade of fuel is used.

It is also the object of this invention, to provide a combined intake and exhaust manifold of unique construction whereby it may be readily attached to one side of an internal combustion engine to communicate with the inlet and outlet ports thereof, and whereby the inflowing and outflowing gases will be directed through adjacent chambers in a novel manner, so that the outflowing or exhaust gases will heat the gases flowing into the cylinders, to the ends desired.

It is also within the scope of the invention, to provide a manifold of the character indicated, which will be comparatively simple, compact, nonencumbering and inexpensive in construction as well as being convenient, practical and efficient in its use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in its preferred embodiment in the accompanying drawings; wherein:

Figure 1 is a side elevation of the improved manifold as applied to a hydrocarbon engine. Fig. 2 is an enlarged longitudinal section of the manifold, taken on the line 2-2 of Fig. 3. Fig. 3 is another longitudinal section of the device, taken on the line 3-3 of Fig. 2. Figs. 4 and 5 are cross sectional views taken on the lines 4-4 and 5-5 of Figs. 2 and 3, respectively.

In carrying out the invention, the combined intake and exhaust manifold embodies an elongated casing or body 1, which is preferably in the form of a casting, and which is illustrated as being composed of a single integral part, although the casing may be made in sections if desired, and as is within the province of the mechanic. The casing 1 is adapted to be disposed at one side of the internal combustion engine, and as illustrated is particularly adapted for application to a "Ford" engine, although the present device may be altered in its proportions and details, within the scope of the appended claims to adapt the manifold to other automobile and kindred engines.

The casing 1 is provided with a longitudinal partition 2 extending from end to end, between the sides thereof and providing a relatively narrow intake chamber 3 at one side, and a relatively wide exhaust chamber 4 at the other or opposite side.

One end of the casing 1 is formed with an outlet nipple or nozzle 6 communicating with the corresponding end of the exhaust or discharge chamber 4, and having a union or socket nut 6 threaded thereon for attaching the end of the exhaust pipe 6^a thereto in order that the exhaust may pass from the chamber through the pipe 6^a into the atmosphere, as usual.

The intake or inlet chamber 3 is disposed adjacent the outer side 7 of the casing 1, and the outer side 7 of the casing and bottom thereof is provided with a depending tubular inlet arm 8, the lower or free end of which is formed in any suitable manner, as at 9, for the attachment of the carburetor 10 thereto, so that the gaseous vapor or carbureted air may flow from the carburetor 10 through the inlet arm 8 to the intake chamber 3. The inlet arm 8 is disposed intermediate or midway between the ends of the casing 1 to introduce the vapor into the intake chamber 3 midway between its ends.

The inner side or back 11 of the casing 1 adjacent which the exhaust chamber 4 is arranged, is provided at suitably spaced longitudinal points with inlet openings 12 so arranged as to align or register with the exhaust ports of the engine cylinders. As illustrated, four of the inlet openings 12 for the chamber 4 are provided, for a four-cylinder engine, it being understood that the number of openings 12 may be increased or

decreased according to the circumstances. Copper or similar nipples 13 are preferably engaged within the openings 12 for the reception of washers or gaskets thereon between the casing 1 and the engine cylinders, to provide a tight or non-leaking joint.

Tubular portions 14 are provided between the partition 2 and inner side or wall 11 of the casing to provide outlet openings for the chamber 3, which extend through the chamber 4 to communicate with the inlet ports of the engine. As illustrated, a pair of tubular portions 14 are provided, between the two pairs of openings 12, each of the tubular portions or outlets for the chamber 3 being adapted to communicate with the respective pairs of engine cylinders to supply the carbureted air thereto. Tubular portions 16 are also provided between the outer and inner sides of the casing 1 and through the partition 2, intermediate the openings 12 and tubular portions 14, to provide bores through the casing and closed off from the chamber through the casing and closed off from the chambers 3 and 4, through which bores securing bolts or elements 17 may be engaged to engage the body or cylinders of the engine for clamping the casing 1 against the side thereof, as suggested in Fig. 1.

Baffle partitions 18 are provided between the partition 2 and the outer side or wall 7 of the casing within the chamber 3, so as to extend from the opposite sides of the inlet arm 8, over and beyond the tubular portions or outlets 14 of the chamber 3 which extend through the chamber 4 to the inner side of the casing, the baffles or partitions 18 extending around the tubular portions 14 toward the ends of the casing and preferably being integral with the tubular portions 16. Thus the inlet of the chamber 3 opens into the chamber 3 between and at one side of the partitions 18, while the tubular portions or outlets 14 of the said chamber are disposed at the opposite sides of the baffles or partitions 18 between the ends of the said baffles or partitions, and which will cause the inflowing gases or vapor to first pass upwardly and longitudinally over the baffles or partitions and thence around the remote ends of the baffles and thence under the baffles to the outlets 14. In this manner, a thorough circulation and agitation of the vapor or gaseous fuel is provided prior to the admission of the vapor into the cylinders, and whereby the vapor will be properly heated by its contact with the partition 2 dividing the chambers 3 and 4.

A plurality of pins or portions 19 are disposed between and integral with the partition 2 and outer side 7 of the casing throughout the extent of the chamber 3, for facilitating the heating of the vapor.

Nipples 20 are preferably engaged within

the inner ends of the tubular portions or openings 14, for the reception of gaskets or washers thereon for providing a tight joint between the casing 1 and the engine body or cylinders.

In practice, the present manifold may be readily attached to the body or cylinders of the engine, to bring the openings 12 into communication with the exhaust ports of the cylinders, and to bring the openings or outlets 14 into communication with the intake ports of the cylinders. Then, the exhaust gases may be discharged through the openings 12 from the ports of the cylinders into the exhaust chamber 4 of the manifold, which will result in a heating of the casing 1, and especially the partition 2. Consequently, as the inflowing vapor or carbureted air passes upwardly over, around and under the baffles or partitions 18, it will become heated by its contact with the partition 2 and the pins or portions 19 which are integral with the partition so as to be heated. This will result in a thorough heating of the vapor, to enhance the combustion of the vapor, and whereby even poorer grades of fuel may be burned more effectively.

The present manifold is simple and compact in construction, so as not to be cumbersome, and may be inexpensively manufactured, all of the parts being readily cast integral with the exception of the nipples 13 and 20, bolts 17 and nut 6.

The other advantages and capabilities of the present invention will be obvious to those versed in the art without further comment being deemed necessary.

What is claimed is:

1. A combined intake and exhaust manifold comprising a casing having a partition therein forming an intake chamber between the partition and outer side of the casing, and an exhaust chamber between the partition and inner side of the casing, the casing having an inlet and outlet communicating with the intake and exhaust chambers, respectively, the inner side of the casing having openings communicating with the exhaust chamber and providing inlets therefor, there being tubular portions between the said partition and inner side of the casing providing outlet openings for the intake chamber extending through the exhaust chamber, and there being baffle partitions within the intake chamber between the said partition and outer side of the casing, the first mentioned inlet and the said tubular portions being arranged at opposite sides of the baffle partitions.

2. A combined intake and exhaust manifold comprising an elongated casing having a longitudinal partition therein forming an intake chamber between the partition and the outer side of the casing, and an exhaust chamber between the partition and inner

- side of the casing, the casing having an inlet communicating with the intake chamber between the ends thereof, and having an outlet communicating with the exhaust chamber, the inner side of the casing having openings providing inlets for the exhaust chamber, there being baffle partitions within the intake chamber between the said partition and outer side of the casing and extending 10 from the inlet of the intake chamber toward the ends of the casing so that the said inlet is disposed between and at one side of the baffle partitions, and there being tubular portions between the first mentioned partition 15 and inner side of the casing providing outlets for the intake chamber extending through the exhaust chamber and arranged at the opposite sides of the said baffle partitions.
- 20 3. A combined intake and exhaust manifold comprising an elongated casing having a longitudinal partition therein forming intake and exhaust chambers at the opposite

sides thereof, the casing having an inlet communicating with the intake chamber between the ends thereof and having an outlet communicating with the exhaust chamber, there being baffle partitions within the intake chamber between the said partition and outer side of the casing and extending 25 from the said inlet toward the ends of the casing so that the inlet is disposed between and at one side of the baffle partitions, and the casing having openings extending from one side and communicating with the intake 30 and exhaust chambers, those openings which communicate with the intake chamber being arranged at the opposite sides of the said baffle partitions.

In testimony that I claim the foregoing as 40 my own, I have hereto affixed my signature in the presence of two witnesses.

FRANK C. MERREGE.
